[57] CLAIM

The ornamental design for a finger ring, as shown and described.

DESCRIPTION

FIG. 1 is a perspective view of a finger ring showing my new design with a diamond setting shown in broken lines;

FIG. 2 is a perspective view similar to FIG. 1, but showing insertion and removal of a small diamond in the shank of the ring;

FIG. 3 is a front elevational view;

FIG. 4 is a rear elevational view;

FIG. 5 is a right side elevational view;

FIG. 6 is a left side elevational view;

FIG. 7 is a top plan view; and,

FIG. 8 is a bottom plan view.

The broken line showing of the diamond setting, in FIG. 1, is for illustrative purposes only and forms no part of the claimed design.
